UNITED STATES PATENT OFFICE.

TED NICAR, OF SOUTH BEND, INDIANA.

DESIGN FOR A RUBBER HEEL.

54,859.

Specification for Design.

Patented Apr. 13, 1920.

Application filed November 29, 1919. Serial No. 341,543. Term of patent 14 years.

To all whom it may concern:

Be it known that I, TED NICAR, a citizen of the United States, residing at South Bend, in the county of St. Joseph, State of Indiana, have invented a new, original, and ornamental Design for Rubber Heels, of which the following is a specification, reference being had to the accompanying drawings, forming a part thereof.

In the drawings, Figure 1 is a plan view showing my new design of a heel.

Fig. 2 is a side elevation of the heel.

I claim:

The ornamental design for a rubber heel as shown.

TED NICAR.
